UNITED STATES PATENT OFFICE.

SAMUEL STEARLY, OF LIVERMORE, COLORADO.

CALF-WEANER.

SPECIFICATION forming part of Letters Patent No. 433,751, dated August 5, 1890.

Application filed January 2, 1890. Serial No. 335,660. (No model.)

To all whom it may concern:

Be it known that I, SAMUEL STEARLY, a citizen of the United States, residing at Livermore, in the county of Larimer and State of Colorado, have invented certain new and useful Improvements in Calf-Weaners, of which the following is a specification, reference being had therein to the accompanying drawings, in which—

10 Figure 1 represents a perspective view of my improved calf-weaner; Fig. 2, a similar view of a modification of the device.

In the drawings annexed, C designates the nose strap or band, the ends of which are connected together by a buckle, in order that different-sized animals may be accommodated; A, the cheek or head straps, also provided with a buckle to render them adjustable, and connected to opposite sides of the nose-20 strap, and B the brow-band and throat-latch combined, which is also provided with a buckle to enable it to be fitted to different-sized heads, and which is adjustably secured to the cheek-straps at the point of intersection by means of leather clips *a a*, whereby it may be readily moved up and down on the said cheek-straps to accommodate different-sized heads. These bands compose the halter or headstall, and the particular advantage 25 of their arrangement is that they can be readily adjusted so as to fit different-sized animals.

The invention can be as readily used upon a cow or colt as upon a calf, although it is particularly designed for the latter.

35 The nose-band may be spikeless, as shown in Fig. 1, or it may be provided with spikes or staples, as shown in Fig. 2, in which latter case a band or plate *b* will be secured to its under side to prevent dislodgment or displacement of the spikes or staples. Swung to the upper portion of the nose-band by means of rings or loops *c* are two depending plates or pieces F, which are preferably approximately triangular in shape and slightly 40 concavo-convex, the concave faces being turned inward. These swinging plates may be constructed of leather or other material, and are provided with sharpened spikes or staples of a suitable length.

45 It will be observed that when the calf or other animal lowers its head to graze or feed the spiked sections F will automatically swing

forward a sufficient distance to be entirely out of the way; but when the animal raises its head these spiked sections will rest lightly 55 against its mouth and nose, so that in case it attempts to suck its mother the sharpened spikes will prick her teats or udder and compel her to refuse it.

In lieu of the sectional plates F, I may use 60 a single concavo-convex plate of leather or metal, as shown in Fig. 2, and, if desired, I may provide the same with perforations to permit the animal to breathe freely. When leather is used for these plates, I prefer to use 65 staples as spurs, the sharpened limbs of the staples being driven through the leather and then spread slightly to hold them in place and prevent their accidental withdrawal. When metal plates are employed, I prefer to use 70 shouldered spikes and strike up or rivet their inner ends to prevent withdrawal.

This invention provides a simple and effectual weaning device which may be applied to heads of different sizes, and which will not 75 interfere in the least with the feeding and breathing of the animal wearing it.

Having thus fully described my invention, what I claim is—

1. The combination of the adjustable nose-band, the adjustable cheek-straps secured to the nose-band, the adjustable combined brow-band and throat-latch adjustably attached to the cheek-straps so as to slide up and down thereon, and a swinging plate attached to the 80 nose-band and provided with spurs, substantially as described.

2. The combination, with a nose-band C, of the adjustable cheek-straps, the adjustable combined brow-band and throat-latch B, secured to the cheek-straps by clips *a a* and adapted to slide longitudinally thereon, and a pair of independent curved plates F F, hung loosely to the said nose-band C by means of rings *c c*, these plates being provided with outwardly-projecting spikes, as and for the purposes herein set forth.

In testimony whereof I affix my signature in presence of two witnesses.

SAMUEL STEARLY.
